UNITED STATES PATENT OFFICE.

FREDERICK O. BALL, OF DETROIT, MICHIGAN, ASSIGNOR TO BALL & BALL CARBURETOR COMPANY, OF DETROIT, MICHIGAN, A PARTNERSHIP COMPOSED OF FREDERICK O. BALL AND CORNELIA M. BALL.

CARBURETOR.

Application filed June 10, 1919. Serial No. 303,205.

In the operation of a carburetor it is desirable to get sufficient velocity of air through the suction passage to atomize the fuel. With a wide open throttle and a rapid speed of the engine there is a sufficient velocity of the air through the contracted portion of the suction passage, usually in the form of a Venturi tube to accomplish this purpose. When there is a slower speed of the engine with a partially closed throttle there is a sufficient velocity of air past the throttle to accomplish the purpose. In one instance the restriction is at the Venturi tube and in the other instance the restriction is made by the throttle. Where, however, there is a wide open throttle and a slow movement of the motor as is apt to be the condition on a hill with an automobile there is not sufficient velocity of air through the carburetor to properly atomize the fuel. In addition to this the mixture is not usually sufficiently rich to give the maximum power so that there is a lack of a sufficiently rich mixture to give maximum power even though the atomization were complete, which condition is aggravated by a lack of atomization so that the ultimate result is that for all practical purposes, a leaner mixture is provided than the mixture delivered under other conditions. It is desirable, therefore, to supplement the normal fuel supply where there is a slow movement of air through the suction passage so as to give the most efficient mixture under these conditions. If this can be attained automatically a very lean mixture may be provided for other working conditions so that there will be an economy of fuel as well as a satisfactory performance under the varying conditions above mentioned. With the present invention this is accomplished.

The invention is illustrated in the accompanying drawing wherein a carburetor is shown in vertical section.

1 marks the suction passage, 2 the throttle, 3 the Venturi tube, 4 fuel nozzles which as shown project from the walls of the Venturi tube, 5 an annular chamber around the Venturi tube and from which the fuel nozzles lead, 6 a passage connecting the annular chamber 5 with an intermediate chamber 7 formed between the walls of a socket 8 formed in the body of the carburetor and the walls of a metering plug 9. The meter-

ing plug has a metered fuel opening 10 which leads to a passage 11 in the plug and the passage 11 communicates with the chamber 7 by means of a radial passage 12. A fuel passage 13 leads from a float chamber 14 to the metered opening 10. The float chamber has the usual supply connection 15 controlled by a valve 16 and the valve is controlled by a float 17 in the usual manner.

The fuel is regulated by the reduction of pressure or suction at the metered opening 10. The reduced pressure at the Venturi tube is communicated to the passage 11 by way of the nozzles 4, passage 6, chamber 7 and passage 12. The suction may be modified by admitting a certain amount of air preferably from the atmosphere and further it is possible by this method to avoid the negative head necessary where the fuel is delivered in the form of raw fuel to the nozzle. Air is admitted to the passage 18 through a passage 19 in the plug 9. A restricted opening 20 communicates with the passages 18 and 11. A passage 21 also leads from the passage 18 to the chamber 7. With the passages admitting air to the chambers between the fuel restriction 10 and the nozzles 4 the suction at the metered opening 10 follows the suction of the suction passage but this suction is reduced by the introduction of the air. The fuel level is indicated at A—A. The fuel level is approximately at the passage 12 and by reason of the fact that the nozzles 4 extend above the fuel level the leakage of fuel when the carburetor is at rest is obviated. On the other hand the air breaking up the fuel at the level of the chamber 6 maintains the level to which the fuel is delivered approximately at or below the fuel level and the fuel is atomized more or less as it is delivered through the nozzles.

Devices for varying the quality of the mixture under the conditions heretofore set forth are as follows: The chamber 7 is connected with a passage or chamber 22 by a passage 23. The chamber 22 opens to the atmosphere and is controlled by a valve 24. The valve 24 has a stem 25 which terminates in a piston 26. The piston operates in a cylinder 27. The cylinder is connected by a passage 28 with the suction passage at a point above the throttle. A spring 29 is arranged on the stem 25 and operates against

a shoulder 30 on the stem 25 and rests against a shoulder 31 at the end of the cylinder 27. The spring is of sufficient strength to retain the valve 24 in closed position until there is such a preponderance of pressure below the piston 26 as to overcome the spring and open the valve.

When there is a wide open throttle and a slow running motor there is, of course, very little reduction of pressure in the suction passage and consequently a very small reduction of pressure in the cylinder 27. Consequently the preponderance of atmospheric pressure over suction passage pressure is not sufficient to overcome the spring 29 so as to open the valve 24. The valve 24 remains in a closed position and the reduction in pressure in the passage 11 inducing a flow through the metered opening 10 is a pressure between that of the Venturi tube and the atmosphere depending on the size of the openings admitting air into the passage 11 and the size of the nozzles forming a means of communication between the passage 11 and the Venturi tube. These are so proportioned as to give a comparatively rich mixture so that the mixture is better adapted to the higher power desired under such conditions but more particularly it supplements the fuel so as to make up for the lack of atomization. When, however, the motor speeds up or a speed is maintained with a partially closed throttle so that there is a higher velocity at the restrictions of the suction passage there is a corresponding reduction of pressure at the discharge side of the throttle which is communicated through the passage 28 to the cylinder 27 and a consequent reduction of pressure above the piston 26 creates a preponderance of pressure below the piston which overcomes the spring 29 and lifts the valve 24, the amount of the opening being dependent on the degree of reduction of pressure.

As the valve 24 is opened air is admitted to the passage or chamber 7 and communicated to the passage 11 so that the reduction of pressure in the passage 11 is less and in consequence the suction effort on the fuel at the restricted opening 10 is reduced, with a consequent reduction in the quantity of fuel delivered. In addition there is a slightly greater amount of air delivered through the nozzles 4 which also tends to make a leaner mixture.

In the drawings I have shown the parts at rest. In operation the closing of the throttle opens the valve 24. It will be understood that the fuel in the chamber 6 is ordinarily swept out by the air to the level of the floor of said chamber.

What I claim as new is—

1. In a carburetor, the combination of a suction passage having an air intake; a fuel passage communicating with the suction pas-

sage the atmosphere and a source of fuel supply, said fuel passage delivering fuel to the suction passage; and devices varying the air supply to the fuel passage to vary the flow of fuel, said devices acting only with a predetermined reduced pressure in the suction passage and continuing to act during such variation of pressure to enrich the mixture with such reduced suction. 70

2. In a carburetor, the combination of a suction passage having an air intake; a fuel passage communicating with the suction passage the atmosphere and a source of fuel supply, said fuel passage delivering at least the major portion of the fuel to the suction passage; and devices varying the air supply to vary the flow of fuel, said devices acting only with a predetermined reduced pressure in the suction passage and continuing to act during such reduced pressure to enrich the mixture with such reduced suction. 80

3. In a carburetor, the combination of a suction passage having an air intake; a fuel passage communicating with the suction passage, the atmosphere and a source of fuel supply, said fuel passage delivering fuel to the suction passage; and devices varying the air supply to the fuel passage to vary the flow of fuel, said devices being responsive to changes in pressure in the suction passage to enrich the mixture with a reduced suction. 90

4. In a carburetor, the combination of a suction passage having an air intake; a fuel passage communicating with the suction passage, the atmosphere and a source of fuel supply, said fuel passage delivering at least the major portion of the fuel to the suction passage; and devices varying the air supply to the fuel passage to vary the flow of fuel, said devices being responsive to changes in pressure in the suction passage to enrich the mixture with a reduced suction. 100

5. In a carburetor, the combination of a suction passage having an air intake; a throttle valve; a fuel passage communicating with the suction passage, the atmosphere and a source of fuel supply, said fuel passage delivering fuel to the suction passage; and devices varying the air supply to the fuel passage to vary the flow of fuel, said devices being responsive to changes in pressure at the discharge side of the throttle to enrich the mixture as the suction is reduced. 110

6. In a carburetor, the combination of a suction passage having an air intake; a throttle valve; a fuel passage communicating with the suction passage, the atmosphere and a source of fuel supply, said fuel passage delivering at least the major portion of fuel to the suction passage; and devices varying the air supply to the fuel passage to vary the flow of fuel, said devices being responsive to changes in pressure at the dis- 120

125

130

charge side of the throttle to enrich the mixture as the suction is reduced.

7. In a carburetor, the combination of a body having a suction passage; a throttle in the suction passage; a fuel well communicating with the suction passage above the fuel level communicating with a source of fuel supply and communicating with the atmosphere; means for maintaining a constant fuel level in the source of fuel supply;

a valve controlling the passage to the atmosphere; a spring resisting the opening of the valve; and a pressure motor having one side of its active element subjected to variations of pressure in the suction passage 15 at the discharge side of the throttle acting on said valve.

In testimony whereof I have hereunto set my hand.

FREDERICK O. BALL.
